Atty.

UNITED STATES PATENT OFFICE.

JOHN J. BARKER, OF ARLINGTON HEIGHTS, MASSACHUSETTS.

TURRET-LATHE.

1,316,075.

Specification of Letters Patent. Patented Sept. 16, 1919.

Application filed April 8, 1919. Serial No. 288,860.

To all whom it may concern:

Be it known that I, JOHN J. BARKER, a citizen of the United States of America, and a resident of Arlington Heights, in the county 5 of Middlesex and Commonwealth of Massachusetts, have invented certain new and useful Improvements in Turret-Lathes, of which the following is a specification.

This invention relates to turret lathes and 10 has for its object the provision of means whereby the support for the turret may be retained in operable condition even after the bed has become worn from constant use. Heretofore in machines of this class the 15 bed will become worn from the continuous dropping of metal pieces thereon and as a consequence the turret support will be so loosely fitted as to make the machine inoperative or at least put in such a condition 20 that perfect work cannot be done thereon.

To overcome this serious objection, depressions are made in the top of the bed in which are adjustably mounted members on 25 which the support may rest when the bed has become worn.

The invention consists in certain novel features of construction and arrangement of parts which will be fully understood by reference to the description of the drawings 30 and to the claims to be hereinafter given.

For the purpose of illustrating the invention, one preferred form thereof is illustrated in the drawings, this form having 35 been found to give satisfactory and reliable results, although it is to be understood that the various instrumentalities of which the invention consists can be variously arranged and organized, and that the invention 40 is not limited to the precise arrangement and organization of the instrumentalities as herein shown and described, except as required by the scope of the appended claims.

45 Of the drawings:

Figure 1 represents a plan view of a portion of a turret lathe embodying the features of the present invention.

Fig. 2 represents a vertical section on line 50 2, 2, on Fig. 1, and

Fig. 3 represents a sectional detail on line 3, 3, on Fig. 2.

Similar characters indicate like parts throughout the several figures of the drawings.

In the drawings, 10 is a portion of the bed of a turret lathe which may be of any well-known construction.

Superimposed upon the bed 10 is a support 11 which may be moved lengthwise of 60 the bed 10 and clamped in adjusted position as usual in machines of this character.

The support 11 is provided with guide-plates 12, the inner edges of which extend into grooves 13 in the side walls of the 65 slide 14 on which the usual turret 15 is mounted.

By means of a shaft 16, reciprocatory movement is imparted to the slide 14 by any 70 well-known means.

As the machine as thus far described forms no part of the present invention the parts hereinbefore mentioned are not shown or described in detail.

The present invention is limited to the 75 devices for preventing vertical movement of the slide 14 when the machine has become worn from constant use.

When the machine is in use the chips and particles of metal continually dropping 80 upon the forward end of the support 11 will wear away the upper face thereof so that the forward end of the slide will not be given the proper support and as a consequence this slide will have sufficient vertical 85 movement to prevent accurate work being performed upon the lathe.

To prevent this rattling and vibratory movement of the slide, depressions 17 are formed in the upper face of the support 11, 90 said support also having a chamber or slot 18 beneath said depressions 17.

In the depressions 17 are mounted the plates 19 having cylindrical shanks 20 extending downwardly therefrom through the 95 chamber or slot 18.

The lower end of the shanks 20 are threaded to nuts 21 within the slot or chamber 18, these nuts 21 being provided with a plurality of radial holes 22 adapted to 100 receive the end of a pin or other tool by which said nuts 21 may be turned to give vertical adjustment to the plates 19.

The slot or chamber 18 is open at the forward end to provide a means whereby the 105 operating pin or tool may be inserted into the holes 22.

The support 11 is also provided with a set screw 23 for each shank 20 and when the plates 19 have been properly adjusted, these 110

set screws will be forced into contact with said shanks 20 and locked by means of the nuts 24, 25.

When the machine is new, the plates 19 5 will be positioned in the depressions 17 and the slide 14 will rest upon the upper face of the support 11.

As soon, however, as the support 11 becomes so worn that the slide 14 will not move 10 in perfect alinement, the plates 19 are moved upwardly sufficient to rectify the alinement and the machine will then operate as well as when first installed.

Many machines become so worn that they 15 are practically useless and are obliged to be placed in the junk pile but by means of this simple device, their use may be continued for many years.

The device may be installed in new 20 machines to be sold or it may be applied to old machines at any time when they begin to operate imperfectly.

It is believed that the operation and many 25 advantages of the invention will be readily understood without further description.

Having thus described my invention, I claim:

1. In a device of the class described, the 30 combination of a support; a tool-supporting member slidable in said support; vertical members in the forward end of said support; and means for imparting vertical movement thereto.

2. In a device of the class described, the 35 combination of a support; a slide thereon; a turret on said slide; vertical members in the forward end of the support; and means for imparting vertical movement thereto.

Copies of this patent may be obtained for five cents each, by addressing the "Commissioner of Patents, Washington, D. C."

3. In a device of the class described, the combination of a support; a slide thereon; a 40 turret on said slide; vertical members in the forward end of the support; means for imparting vertical movement thereto; and means for locking said members in adjusted position.

4. In a device of the class described, the combination of a support; a slide thereon; a 45 turret on said slide; vertical threaded members in the forward end of the support; and nuts coacting with said threaded members. 50

5. In a device of the class described, the combination of a support having depressions in the upper face thereof and an open ended slot beneath said depressions; a turret supporting slide on said support; plates in said 55 depressions having downwardly extending threaded shanks; and nuts on said shanks positioned in said slot and prevented from moving endwise by the walls thereof.

6. In a device of the class described, the 60 combination of a support having depressions in the upper face thereof and an open ended slot beneath said depressions; a turret-supporting slide on said support; plates in said 65 depressions having downwardly extending threaded shanks; nuts on said shanks positioned in said slot and prevented from moving endwise by the walls thereof; and means for locking said shank in adjusted vertical position.

Signed by me at 4 Post Office Square, Boston, Mass., this 7th day of April, 1919.

JOHN J. BARKER.
